DESIGN FOR A COMBINED SMOKING STAND AND LIGHTER

Bert A. Dickerson, Decatur, Ill.

Application June 19, 1935, Serial No. 57,334

Term of patent 3½ years

To all whom it may concern:

Be it known that I, Bert A. Dickerson, a citizen of the United States, residing at Decatur, in the county of Macon, and State of Illinois, have invented a new, original, and ornamental Design for a Combined Smoking Stand and Lighter, of which the following is a specification, reference being had to the accompanying drawing, forming part thereof, in which—

The figure is a perspective view of a combined smoking stand and lighter, showing my new design.

I claim:

The ornamental design for a combined smoking stand and lighter as shown.

BERT A. DICKERSON.
